UNITED STATES PATENT OFFICE.

HENRY JOHNSON, OF DETROIT, MICHIGAN.

JACK.

1,289,795.

Specification of Letters Patent. Patented Dec. 31, 1918.

Application filed March 8, 1918. Serial No. 221,232.

To all whom it may concern:

Be it known that I, HENRY JOHNSON, a subject of the King of Sweden, residing at Detroit, in the county of Wayne and State 5 of Michigan, have invented new and useful Improvements in Jacks, of which the following is a specification.

This invention comprehends the provision of a pneumatic jack of a compound nature, 10 wherein the lifting element is subjected to the air pressure at spaced superimposed points in its length thereby increasing the lifting power, as well as effecting the rapid elevation of said element proportionately 15 with regard to the load to be lifted, and finally providing a double resistance for the object supported upon the jack, the latter possessing maximum strength and durability.

20 While a general application of the invention is contemplated, it is primarily intended for hoisting vehicle bodies or the like, and it embodies among other features a pair of telescopic communicating cylinders, one of which constitutes a support for the jack and the other the lifting element, the latter being provided with a piston operating within the lowermost cylinder so that when air under pressure is introduced 25 into the cylinders the upper end of the lifting element as well as the piston are subjected to pressure for the purpose above mentioned.

Another important characteristic of the 30 invention resides in providing the upper end of the supporting cylinder with a safety valve adapted to be opened when the lifting element is in full extended position, thus allowing the excess of air pressure to escape 35 through a suitable outlet, should under any circumstances air be forced into the cylinders after the lifting element has been adjusted to its maximum extent.

The nature and advantages of the invention 40 will be readily apparent when the following detailed description is read in connection with the accompanying drawings, the invention residing in the construction, combination and arrangement of parts as 45 claimed.

In the drawing forming a part of this specification, like numerals of reference indicate similar parts in the several views, and wherein:—

55 Figure 1 is a vertical sectional view

through the jack showing the lifting element partly adjusted;

Fig. 2 is a similar view showing the lifting element subjected to its maximum height 60 and the safety valve opened;

Fig. 3 is a top plan view;

Fig. 4 is a transverse sectional view taken on the line 4—4 of Fig. 2.

The jack constructed in accordance with 65 my invention essentially consists of a pair of hollow cylindrical members 10 and 11 respectively, the latter being telescopically fitted within the former as illustrated. In 70 use of the jack the cylinder 10 constitutes the lifting element, while the cylinder 11 75 constitutes the supporting cylinder, which rests upon the ground or surface. In the further description of the invention these cylinders will be referred to accordingly. 75

The supporting element 11 is provided with a relatively broad base 12, while the opposite end of this element is interiorly threaded for a portion of its length to accommodate the plug 13 which constitutes a 80 closure for the member 11. The plug is provided with a restricted central aperture to slidably receive the piston rod 14, which depends from the upper end of the lifting element 10. A piston 15 is carried by the 85 lower extremity of the rod 14 and operates within the supporting element 11. The piston 15 may form an integral part of the rod 14 or may be otherwise detachably associated with the rod in any suitable manner. 90 A leather disk or packing 16 surrounds the piston rod 14 and reposes upon the plug 13 in the upper end of the supporting element 11. The packing is slightly upturned as at 95 17 to snugly engage against the piston rod 14 and the wall of the lifting element 10 to provide a fluid-tight connection between these parts. A washer 18 also surrounds the piston rod 14 and rests upon the disk 16. Any suitable means may be employed 100 for maintaining the washer 18 secured to the plug 13. The washer is provided with inner and outer peripheral grooves 19 in each of which is arranged an expandable ring 20. The rings are utilized to hold the 105 disk or packing 16 in effective engagement with the piston rod 14 and the wall of the lifting element 10, the rings exerting a pressure against the upturned portion 17 for this purpose. The piston rod 14 is provided 110 with a longitudinal bore 21 including a

laterally disposed branch 22 disposed substantially in alignment with the air intake opening 23 of the lifting element 10. The bore 21 opens at the opposite end of the 5 piston rod 14 so that when air under pressure is introduced into the lifting element 10 it enters the bore 21, passing therethrough into the supporting cylinder 11. A disk of suitable packing material 24 is arranged 10 against the bottom of the piston 15 and has its peripheral edge downturned as at 25 to effectively engage the wall of the cylinder 11 to prevent the escape of air therefrom. A washer 25' bears against the 15 disk 24 and is provided with a peripheral groove 26 for the reception of an expansible ring 27, which exerts a pressure against the downturned edge portion of the packing to maintain the latter against the wall of the 20 cylinder 11. A hollow substantially V-shaped member has its stem portion 28 threaded within the bore 21 of the piston 15 with the cross piece or head 29 of said member bearing against the washer 25' to 25 hold the latter properly positioned with respect to the disk 24. The piston rod 14 passes through a restricted central opening in the top of the lifting element 10 and is provided with a reduced exteriorly threaded 30 portion 30. A yoke 31 which engages the object to be lifted, rests upon the upper end of the lifting element 10 and is provided with an internal shoulder 32. A suitable nut 33 is secured to the threaded extremity 35 30 of the piston rod and is provided with a shoulder 34 which engages the shoulder 32 of the yoke thus holding the latter fixed relatively to the lifting element 10 as will be readily understood. In addition to maintaining the yoke 31 in proper position upon the element 10, the nut 33 also serves to hold the piston rod 14 operatively associated with said lifting element. The nut 33 is provided with openings 35 to accommodate a suitable 40 45 tool when it is desired to effect an adjustment of the nut.

In practice, a rubber hose (not shown) leading from a compressed air tank, or a motor operated air pump, (not shown) is 50 coupled to the intake nipple 23 of the lifting element 10, or to the nipple 23' of the supporting element 11. The nipple has housed therein any well known form of valve which opens inwardly, and herein 55 indicated generally at 36. As air under pressure is introduced into the lifting element 10 or the supporting element 11, a portion of the air enters the bore 21 of the piston 14 and is obviously conveyed into 60 the opposite cylinder. As the respective cylinders become filled with air the requisite pressure is exerted against the top of the lifting element 10 and the piston 15 to elevate the lifting element 10 upon the element 65 11. The construction defines a jack of a

compound nature, which in addition to possessing a maximum lifting power, effects an adjustment of the lifting element 10 with considerable rapidity in proportion to the weight of the load to be elevated. As the 70 lifting element 10 is elevated the piston 15 forces from the cylinder 11 through an outlet port 37, the air which occupies the space between the piston 15 and the plug 13. It will be noted that the space 38 is provided 75 about the cylinder 11, and the outlet port 37 is in direct communication with the space so that air forced from the cylinder 11 will pass freely through the port 37 to the atmosphere. When the lifting element 10 has 80 been elevated to the desired extent, the air tube not shown is separated from the nipple 23 thus allowing the valve 36 to close. The air within the lifting element 10 and also within the cylinder 11 provides a double 85 resistance to the load supported upon the yoke 31. Manifestly, the invention not only provides a simple compact construction and arrangement of parts, but a jack possessing maximum lifting power, strength and durability. 90

In carrying out my invention, use is made of a safety valve to prevent injury to the jack as an entirety, by excessive air pressure, after the lifting element 10 has assumed its full extended position. In this connection a valve casing 39 is fitted within the plug 13 and formed to provide a valve seat 40. A valve 41 normally engages said seat and includes a stem 42 which projects 100 through the casing 39 terminating an appreciable distance below the plug 13. A coil spring 43 encircles the projecting portion of the stem and has one end bearing against a pin 44 passed transversely through 105 the stem, while the opposite end of the spring contacts the adjacent end of the casing 39, so that the spring operates to maintain the valve normally seated. Now, when the lifting element 10 reaches the limit of its 110 adjustment in an upward direction, and air under pressure continues to enter the intake opening 23, the excessive pressure within the cylinders would obviously have a very detrimental effect upon the jack, if it were not 115 for the fact that the piston 15 is forced into engagement with the valve stem 42, thus unseating the valve and permitting this excessive pressure to pass through the casing 39 to the outlet port 37 of the cylinder 11. 120 Of course, when the piston 15 is moved away from the valve stem the valve is automatically seated under the influence of the spring 43. When it is desired to lower the lifting element 10, it is only necessary to move the 125 valve 36 inwardly to an open position thus allowing the air to escape from both of the cylinders 10 and 11 respectively. Obviously, for the purpose the air passes upwardly 130 from the cylinder 11 through the bore 21

of the piston rod 14 into the cylinder 10. In this manner the lifting element 10 returns from its adjusted to its normal position gradually, and without any danger to the 5 operator or injury to the object supported upon the jack.

It is also the purpose of the invention to provide a scraper, in the form of an annulus 50 of leather or other suitable material, 10 which forms a dust proof joint between the lifting and supporting elements and also acts to scrape away dust or dirt from the inner wall of the lifting element.

In addition, a handle 51 is pivotally secured to the base of the supporting element 15 for convenience of positioning the jack beneath an object.

While it is believed that from the foregoing description the nature and advantages 20 of the invention will be readily apparent, I desire to have it understood that I do not limit myself to what is herein shown and described, as the same merely constitutes the preferred embodiment of the invention, and 25 that such changes may be resorted to when desired as fall within the scope of what is claimed.

Having described the invention, what is claimed is:—

30 1. In a pneumatic jack, a pair of superimposed communicating cylinders, one of which is slidably mounted upon the other, a valve controlled air inlet in said movable cylinder, a piston carried by said cylinder and operating within the lowermost cylinder, and said latter cylinder having an air 35 exhaust located above said piston.

2. In a pneumatic jack, a pair of superimposed communicating cylinders, one of said 40 cylinders being slidably mounted upon the other, the movable cylinder having a valve controlled air inlet port, a piston rod disposed within the movable cylinder, a piston carried by said rod and operating within the 45 other cylinder, the latter mentioned cylinder having an air exhaust port located above the piston, a yoke mounted upon the movable

cylinder, and means common to both the piston rod and said yoke for holding said part fixed relatively to said movable cylinder. 50

3. In a pneumatic jack, a pair of superimposed cylinders, one being slidably mounted upon the other, said movable cylinder having a valve controlled air inlet port, a 55 piston rod carried by the movable cylinder, a piston on the lower end of said rod operating within the other cylinder, said rod having a longitudinally disposed bore for establishing communication between said cylinders, and the latter mentioned cylinder having an air exhaust port located above said piston. 60

4. In a pneumatic jack, a pair of superimposed communicating cylinders, one of 65 said cylinders being slidably mounted upon the other, said movable cylinder having a valve controlled air inlet port, the other cylinder having an exhaust port adjacent the upper end thereof, a piston in one of said 70 cylinders, a normally closed release valve carried by the said upper end of the latter mentioned cylinder, and said valve being opened by means of said piston when the latter reaches the limit of its adjustment in 75 one direction.

5. In a pneumatic jack, a pair of superimposed communicating cylinders, one of said cylinders being slidably mounted upon the other, said movable cylinder having a 80 valve controlled air inlet port, the other cylinder having an exhaust port adjacent its upper end, a piston in one of said cylinders, a spring pressed release valve carried by the upper end of the latter mentioned cylinder, 85 said valve being normally seated and including a stem projecting within said cylinder and terminating in the path of movement of the piston within said cylinder, whereby said valve is opened by the piston when the 90 latter reaches the limit of its adjustment in an upward direction.

In testimony whereof I affix my signature.
HENRY JOHNSON.
